CAN OPENER

Thur Schmidt, Chicago, Ill.

Application March 18, 1947, Serial No. 735,350

2 Claims. (Cl. 30—9)

(Granted under the act of March 3, 1883, as
amended April 30, 1928; 370 O. G. 757)

1

The invention described herein, if patented may be manufactured and used by or for the Government for governmental purposes, without the payment to me of any royalty thereon.

This invention relates to can openers of the type employing a rotary cutter, a feed wheel and pressure member to maintain the can in proper frictional engagement with the feed wheel, and has for a primary object to generally improve their construction and operation.

More specifically, it is an object of the invention to improve the body member or post of can openers of this type by utilizing metal tubing and flattening the same at certain points to provide clearance and mounting facilities for the rotary cutter, feed wheel and pressure plate.

A further object of the invention resides in the provision of a can opener of the type described formed primarily of standard stainless steel tubing to thereby provide longer life, ease of fabrication, high tensile strength, and an inherent lustre.

Other objects and advantages of the invention will be apparent from the following description when taken in connection with the accompanying drawings, in which,

Figure 1 is a side elevational view of the novel can opener in use.

Figure 2 is a longitudinal sectional view taken on line 2—2 of Figure 3.

Figure 3 is a rear elevational view of the opener.

Figure 4 is a front elevational view of the opener with parts broken away.

Figure 5 is a plan view of the complete apparatus.

Figure 6 is a perspective view of the pressure plate with parts broken away to more clearly show the construction, and

Figure 7 is an enlarged sectional view taken on line 7—7 of Figure 2.

Referring to the drawings in greater detail, the numeral 1 indicates a tubular body member formed of standard steel tubing, the steel being preferably of the stainless variety having a bright finish. This body member or post may be secured to a clamping element 2 by means of rivets or pins 3, and threaded clamping element 4 is threaded into the base plate 5 of the clamping element 2 for cooperation with the upper plate 6 of the clamping element. If desired, the base plate 5 may be provided with a plurality of openings 7 by which the plate may be permanently fixed to a table or the like in lieu of being removably clamped thereto between the clamping elements 5 and 6.

2

The tubular member 1, adjacent its upper end, is flattened for the purpose of mounting the usual rotary cutter and feed wheel and for providing the necessary clearance for these members. The lower portion of the flattened section, as clearly indicated in Figure 2, is provided with a transverse opening in which is mounted a bushing 8, the bushing being rotatably mounted and held against endwise movement by means of clamping plates 9 and 10. These clamping plates are secured to each other and to the flattened portion of the tubular member by means of rivets 11, and the bushing is held against endwise movement by means of the annular flanges 12 and 13 formed on the respective plates and contacting the enlargement 14 formed on the periphery of the bushing. This bushing receives the journal 15 of the feed wheel 16 which is eccentrically mounted in the bushing so that the feed wheel 16 may be shifted toward and from the rotary cutter.

The journal 15 is provided with a disc portion 17 and this disc is provided with a central aperture and two diametrically opposed apertures to receive fastening screw 18 and pins 19 the latter being integrally formed on the feed wheel and serving to securely lock the same with respect to the disc 17 of the journal 15. The opposite end of the member 15 is provided with flattened portions to receive similar flattened portions formed on the wall of an aperture in the handle 20 and a nut 21 is provided for detachably securing the handle in place. The bushing 8, as above mentioned, is rotatably mounted for the purpose of shifting the feed wheel 16, and to this end a handle 22 is passed over the journal 15 and secured to the bushing 8 by means of a screw 23.

Slightly above the feed wheel 16 the flattened portion of the tubular member 1 is provided with an inclined opening in which is mounted a bushing 24 for rotatably supporting the journal 25 of the inclined rotary cutter 26. This bushing, similar to bushing 8, is held against endwise movement by flanges 27 and 28 formed on the retaining plates 9 and 10, respectively. The journal 25 is held in position in the bushing 24 by suitable locking means such as nut 29.

The pressure plate in this construction is indicated by the numeral 30 and is provided with the usual pressure feet 31 for cooperation with the feed wheel 16 in feeding the cans to the cutter 26. The pressure plate is provided with a semi-circular band 32 at its upper end which is secured by means of rivets 32' to a cap portion 33 slidably mounted on the upper end of the tubular member 1. As well understood, the pres-

sure feet 31 serve to firmly press the flange of the can against the feed wheel 16 and for this purpose the compression spring 34 is employed. The lower end of the spring 34 engages a washer on the lower end of bolt 35 and the upper end of this bolt passes through a central opening in cap 33 and has its head 36 resting upon the exterior surface thereof. The upper end of compression spring 34 engages the base of a cup 37, the latter being fixedly secured within the upper end of the tubular member 1 by means of rivets 39.

Rotary movement of the cap 33 with respect to the upper end of the tubular member 1 is prevented by reason of a vertical slot 40 formed in a wall of the cap and engaging over a protuberance 41 formed on the post adjacent the upper end thereof. This pin and slot connection serves as a guide for the pressure plate 30, and the plate is further guided and maintained in its proper relative position by means of fingers 42 formed on the plate 30 and engaging over guide ribs 43 formed by the adjoining edges of the retainer plates 9 and 10 for the bushings 8 and 24.

In the operation of the device, the arm 22 is swung upwardly in the usual manner to lower the feed wheel 16 and permit introduction of the can, to be operated upon, into position against the cutter 26; thereafter the handle is swung downwardly to raise the feed wheel and thereby force the can against the cutter and the pressure feet 31. In this operation the pressure plate is guided by the pin and slot connection 40-41 and by the fingers 42 on the pressure plate engaged over the ribs 43. The crank 20 may now be operated in the usual way to rotate the feed wheel 16 to thereby rotate the head of the can against the rotary cutter 26 and thus sever the head from the body of the can.

From the foregoing description and the attached drawings, it will be apparent to those skilled in the art that I have devised an extremely sturdy construction of can opener of the rotary cutter and feed wheel type; that the adaptation of standard steel tubing for the support for the operating parts tends to easier fabrication and consequently a lower cost of manufacture; that

the tensile strength of the apparatus is greatly increased; that a novel and compact arrangement for the spring-pressed pressure plate is provided, and that means are provided for accurately guiding the plate at both its upper and lower extremities.

In accordance with the patent statutes, I have described what I now believe to be the preferred form of the invention but inasmuch as various minor changes may be made in structural details without in any way departing from the spirit of the invention it is intended that all such changes be included within the scope of the appended claims.

I claim:

1. A can opener comprising a tubular body member having a flattened portion, a pair of bushings extending through said flattened portion, a rotary cutter journaled in one of said bushings, a rotary feed wheel journaled in the other of said bushings, and retaining plates secured against the flattened faces of said flattened portion and engaging the ends of said bushings to secure the same against endwise motion.
2. A can opener comprising a tubular body member having a flattened portion, a pair of bushings extending through said flattened portion, a rotary cutter journaled in one of said bushings, a rotary feed wheel journaled in the other of said bushings, retaining plates secured against the flattened faces of said flattened portion and engaging the ends of said bushings to secure same against endwise motion, and a pressure plate yieldingly mounted on said member, and flanges on said retaining plates for guiding said pressure plate.

THUR SCHMIDT.
